US0D1010266S

(12) **United States Design Patent** (10) **Patent No.:** **US D1,010,266 S**
(45) **Date of Patent:** **** Jan. 2, 2024**

(54) **PORTABLE HOT PRESS**

(71) Applicant: **FOSHAN MAINA TECHNOLOGY CO., LTD**, Foshan (CN)

(72) Inventor: **Yisheng Wu**, Huangshan (CN)

(**) Term: **15 Years**

(21) Appl. No.: **29/778,808**

(22) Filed: **Apr. 15, 2021**

(51) **LOC (14) Cl.** **07-05**

(52) **U.S. Cl.**

USPC **D32/69**

(58) **Field of Classification Search**

(57) **CLAIM**

The ornamental design for a portable hot press, as shown and described.

DESCRIPTION

FIG. 1 is a perspective view of a portable hot press showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the portable hot press that form no part of the claimed design.

1 Claim, 8 Drawing Sheets
